UNITED STATES PATENT OFFICE

HOMER E. GILLAND AND WILLIAM H. GILLAND, OF SAGINAW, MICHIGAN.

ROLLING WINDOW-SCREEN.

No. 818,642.

Specification of Letters Patent.

Patented Feb. 27, 1906.

Application filed May 11, 1903. Serial No. 156,593.

To all whom it may concern:

Be it known that we, HOMER E. GILLAND and WILLIAM H. GILLAND, citizens of the United States, residing at Saginaw, in the county of Saginaw and State of Michigan, have invented certain new and useful Improvements in Rolling Window-Screens; and we do hereby declare the following to be a full, clear, and exact description of the invention, such as will enable others skilled in the art to which it appertains to make and use the same.

This invention pertains to extensible rolling window-screens, and relates more particularly to window-screens mounted on spring-rollers carried by the window-frame and having their upper ends fastened to the vertically-slidable window-sash, so that the screen unrolls as the sash is raised, thereby keeping the opening covered by the screen. To adapt such a screen to suit various widths of windows, it is made of two overlapping parts that may be slid past each other, and the roller is made extensible.

Our invention is illustrated in the accompanying drawings, in which—

Figure 1 is a part view of a window with our improvement attached. Fig. 2 is a vertical section on the line xx of Fig. 1. Fig. 3 is a perspective view of the extensible roller, its extensible case and bracket, and the extensible cover.

As is clearly shown in the drawings, the extensible screen 1 is fixed at its upper end to the window-sash 2, and its lower end is mounted on a spring-actuated roller 3, preferably of metal, to avoid warping.

The screen is laterally extensible, as above noted, and the roller 3 is also extensible to suit windows of various widths. In order to protect the rolled screen from rain, snow, and dust, we mount the roller 3 in a metal case 4, secured to the window-frame or to the sill S, as shown in Figs. 1 and 2. The case is also extensible, and consists in two approximately semicylindrical tube-sections 4^a and 4^b, one of which is provided on its edges with inwardly-turned flanges 4^c. The section 4^a is of proper size to telescope within the section 4^b and is held in place by engagement of its edges in the flanges 4^c. Ends 4^{a'} and 4^{b'} are provided for the telescoping tubes, and these ends have slots, in one of which, 4^{a''}, revolves the journal 3^a of the roller 3, and in the other

slot 4^{b''} fits the flattened non-rotatable spear 55 of the roller 3. These ends 4^{a'} and 4^{b'} serve as roller-brackets.

As is shown in Fig. 2, the upper edge of the case 4 is normally back of the plane of the screen to permit the latter to roll and unroll vertically. One side of the case is open toward the sash, and the sash when closed almost covers the opening; but there still remains between the sash and the upper edge of the case a slot of sufficient width to permit the movement of the screen. To make the roller and screen perfectly weatherproof when the sash is closed, we provide the extensible cover 5. This cover is secured to the sash 2 and projects outwardly to overlap the case 4 when the window is closed. It is made in two telescoping sections 5^a and 5^b of the same general construction as case 4. It has a flange 6, which is screwed or otherwise secured to the sash 2, and this flange 75 may be made to serve the additional purpose of a nailing-strip for securing the upper end of the screen to the sash.

When the sash is closed, the lower edge of the sash forms the closure for the side of case 4, and the overlapping cover 5 closes down upon the case, rendering it perfectly weatherproof and protecting the roller and screen. Both the case and its cover can be easily attached to a window and easily adjusted thereon.

While we have shown and described our improved device as fastened to the upper surface of the window-sill S, it might also be applied to the upper sash of the window by being fastened to the upper part of the frame instead of the sill. Where a metallic window-frame is used, the case 4 may be fitted into a depression in the sheet-metal sill or, if desired, may be made integral with the sill 95 instead of separable, as we have shown it in the application illustrated by Fig. 2.

What we claim as our invention, and desire to secure by Letters Patent, is—

A rolling screen for windows comprising an extensible sectional spring-actuated roller, screen members mounted on each roller-section, the adjacent edges of the screen members adapted to overlap each other, a sectional telescopic casing in which the roller is journaled, the casing adapted to receive and protect the screen members and provided with a slot through which the screen

members pass, the sections of the casing each provided with integral slotted ends, a curved sectional telescoping cover for the slot, and flanges carried by the cover - sections and serving as a nailing-strip whereby to simultaneously secure the cover and the upper edges of the screen members to the sash of a window.

In testimony whereof we affix our signatures in presence of two witnesses.

HOMER E. GILLAND.
WILLIAM H. GILLAND.
